UNITED STATES PATENT OFFICE.

PAUL F. DEGENKOLB, OF ITASCA, ILLINOIS.

BOX-OPENING DEVICE.

1,354,893.

Specification of Letters Patent.

Patented Oct. 5, 1920.

Application filed April 5, 1920. Serial No. 371,253.

To all whom it may concern:

Be it known that I, PAUL F. DEGENKOLB, a citizen of the United States, residing at Itasca, in the county of Dupage and State of Illinois, have invented certain new and useful Improvements in Box-Opening Devices, of which the following is a specification.

This invention relates to a box equipped 10 with a cover opening device which serves also as a cover handling means.

An exemplification of this invention in its preferred form is shown in the accompanying drawing wherein Figure 1 represents in 15 side elevation a conventional box with its cover in place; Fig. 2 the box with its cover partially raised by operation of the present device; Fig. 3 an enlarged transverse section on line 3-3 of Fig. 1; and Fig. 4 an 20 enlarged side elevation of the opening device.

The box A shown in the drawing may be of any usual kind, preferably of metal, having side walls 5 from which is outwardly extended a bead or shoulder 6 near the upper edge. Arranged to fit over the box is a 25 cover B whose walls 7 may overlap the upper portion of the box walls, and slide down thereover as far as the bead 6. Boxes 30 of this character are well known and require no further description. This invention, however, may be applied to boxes otherwise formed, and this should be clearly understood from the beginning.

The opening device forming the subject 35 of this invention may comprise a handle 10 that is laterally extended from the cover adjacent its lower edge. From this handle about midway of its length depend companion ears 11 adapted to receive between them a pin 12 which provides a hinge mounting 40 for a lever 13 that may also be formed with companion ears 14 adapted to lie adjacent the ears 11. The normal position of the 45 lever relative to the handle is as indicated in Figs. 1 and 4, this being assured through the medium of a spring 15 which is preferably coiled around the pin 12 and arranged to present its ends 16 one against the 50 handle and the other against the lever near its outer end.

As best shown in Fig. 4, the lever is provided with an acting end 17 which lies adjacent the cover edge. When the cover is 55 attached to the box this lever end 17 will rest upon the bead 6 in such a manner as to exert pressure thereupon when a corre-

sponding pressure is applied to the opposite end of the lever, such as to move it to the position shown in Fig. 2. Having started 60 the cover from the box, the cover may be removed conveniently through the medium of the handle 10 and lever 13 so as to be placed away as desired.

The box opening device of this invention 65 may be very simply formed. In use it operates with certainty, and affords a desirable means of both loosening and removing a box cover. Changes or modifications are, of course, possible without sacrifice of the features that are novel to this invention, and accordingly I do not desire to be limited to the exact form shown except as defined in the appended claims.

I claim:

1. In combination, a box having a bead outwardly extended from its walls near the edge adjacent an open side of the box, a cover having a flanged wall adapted to fit over the box sides and to extend adjacent 80 the bead thereon, and an opening device comprising a handle extending laterally from the cover, a lever hinged to the handle having an acting end adapted to lie adjacent the bead, and a coiled spring arranged 85 concentrically of the hinge axis operating to hold the acting end of the lever adjacent the handle, the lever when moved against the tension of the spring operating to separate the cover from the box, substantially 90 as described.

2. In combination with a box, a cover therefor, and an opening device comprising a handle laterally extended from the cover and provided at opposite sides with depending ears, a lever arranged operatively to the handle and formed with laterally extending ears adapted to lie adjacent those projected from the handle, a pintle connecting all four ears to establish a hinge connection 100 between the lever and handle, and a spring coiled around the pintle with its ends projected from the box and between the lever and handle so as to exert an influence tending to spread the ends of the lever and handle which are remote from the box, the lever end adjacent the box being adapted to engage therewith so as to separate the box from the cover when the opposite end of the lever is moved toward the handle, substantially 105 as described.

PAUL F. DEGENKOLB.
